UNITED STATES PATENT OFFICE

HOWARD E. SHEELEY, OF MICHIGAN CITY, INDIANA

ADJUSTABLE REEL

Application filed November 3, 1930. Serial No. 493,183.

My invention relates to the art of reeling and has special reference to the art of handling rope, wire, light chains, sash cord, heavy twine, electric cable or conductor wire, 5 and like material which is commonly sold and used in coil form.

It is well known that electric wires and cables of varying sizes are customarily sold in coils of 500 lineal feet, and that the openings in these coils vary not only with the varying size of the wire, but different manufacturers make different sized openings for the same size of wire, hence the need of an adjustable reel to aid in the uncoiling of 10 wire for all sorts of electric installation such as commercial wiring for lighting, refrigeration, elevator operation, telephone and telegraph exchanges, burglar alarms and the like.

20 While my improved reel is especially adaptable to such uses as indicated it is obvious that it may be used for unwinding coils of any material that are normally sold without a supporting spool.

25 However the primary object of my invention is to facilitate and therefore expedite electric wiring operations such as indicated above by feeding electric conductor wire or cable to the electrician occupied with its installation, and to do this without kinking or 30 tangling in the coil.

Still another object of my invention is to provide such a structure as defined above as will permit the uncoiling without back lash, 35 and which is capable of ready adjustment to provide for the handling of coils of varying sizes, such as indicated above.

While certain of the above objects were attained in my prior Patent No. 1,557,887, issued to me October 20, 1925, by my present invention they are attained by a self-contained and unified structure which is much simpler in operation, easier of manufacture, and more efficient in use.

40 The following specification clearly sets forth the novel structure by which the above objects are attained.

Having reference to the drawings:

Fig. 1 is a plan view of the duplex form 50 of my improved reel, showing one reel col-

lapsed, and one reel expanded with a coil of wire thereon.

Fig. 2 is a side elevation of that form of my device shown in Fig. 1 taken in the direction of the arrow.

Fig. 3 is a detail perspective view showing the preferred construction at the end of the spokes of the reel members.

Fig. 4 is a vertical longitudinal sectional view taken on line 4-4 of Fig. 1.

Fig. 5 is a detail view in perspective of the duplex form of my reel stand.

Fig. 6 is a detail view in perspective of the single form of my reel stand.

With reference to the several figures of the drawings, specifically my improved reel comprises a stand 10, which in the duplex form consists of two members 11 brazed together as shown in Fig. 5. Each member 11 comprises a base portion 12, bent to the general form of the letter U; an upright 13, and a horizontal bearing member 14. Mounted on this horizontal member is an extended or elongated sleeve 15 provided on its outer surface with threads or ridges 16 for a purpose that will presently be described. At the outer end of the horizontal member 14 is fixed a suitable thrust keeper 17. At the inner end of said member 14 is a short collar 18 which acts as a retaining member for spring 19 coiled on member 14 between said sleeve 15 and collar 18. The function of spring 19 is to prevent spinning of the coil and resulting back lash.

Rigidly mounted on sleeve 15 at its inner end is a spoked reel member 20 comprising a hub 21 having fixed therein suitable spokes 22. These spokes 22 are so formed at their outer ends as to provide suitable guides 23 for flexible coil holding members 24 and enlarged wear blocks 25, which reduce the wear on the flexible members 24. Said flexible members 24 are suitably secured to said spokes 22 as indicated at 26.

Slidably mounted on sleeve 15 between keeper 17 and reel member 20, is a folding reel member 27 having a hub 28 on which are pivoted spokes 29 of a number to correspond with the fixed spokes 22 of member 20. Said spokes 29 are formed at their outer ends with

guides 30 and wear blocks 31 corresponding with like features on spokes 22. At their inner ends spokes 29 are pivoted near their outer faces as indicated at 32 so that when 5 expanded the inner face edges 33 of said spokes 29 will engage with the threads or ridges 16 on sleeve 15 to prevent inward longitudinal movement of hub 28 on sleeve 15.

Spokes 29 are provided on their outer faces 10 with a series of sloping slots 34 in which are anti-friction rollers 35 mounted on pins 36. It is obvious that a series of holes could be substituted for the slots without departing from my invention. The flexible coil members 15 24 pass through guides 30 at the outer ends of spokes 29, thence under the anti-friction rollers 35 to a suitable anchorage as indicated at 37.

It is well known that electric wiring, electric cable, and similarly formed articles are sold in coils, which are secured from uncoiling by twine or wire wound around the rim of the coil transverse thereto. This leaves a central opening as is well known. In the 20 use of my improved reel the flexible members 24 are adjusted in the slots 34 to the approximate diameter of the opening of the coil to be handled. Then the spokes 29 are collapsed, the coil placed thereover, then hub 28 25 is slid outwardly on sleeve 15 until the tension on the flexible members 24 causes the inner edges 33 of the spokes 29 to engage the threads or ridges 16 on the sleeve 15, thereby 30 making them rigid, which rigidity will be maintained until the entire coil is unwound.

While I have shown the standard of my improved reel formed from a single bent element, it is within the purview of my invention to form the same with any rigid base and 40 an upright to which the horizontal bearing 45 may be suitably attached.

It is also within the scope of my invention to form the spokes of my device of wood or other solid matter as well as from sheet metal 45 as shown.

My improved reel may be supported in banks if desired. It is also capable of being mounted on vertically disposed bearing members.

Having thus fully described my invention, 50 what I claim is:

1. An adjustable reel for handling open center coils of wire or like material comprising an elongated bearing member having a rigid side reel member secured at one end thereof, a collapsible side reel member slidably mounted on said bearing member, adjustable flexible coil supporting members connecting said side reel members, and means 55 permitting adjustment of said coil supporting members.

2. An adjustable reel for handling open center coils of wire or like material comprising an elongated bearing member having a rigid side reel member secured at one end 60

thereof, a collapsible side reel member having foldable arms and slidably mounted on said bearing member, and flexible coil supporting members connecting said side reel members at approximately the greatest diameter thereof and adapted to expand the arms of said collapsible reel member, upon sliding the collapsible member away from the rigid member.

3. An adjustable reel for handling open center coils of wire or like material comprising an elongated bearing member having a rigid side reel member secured at one end thereof, a collapsible side reel member having foldable members and slidably mounted on said bearing member, and flexible coil supporting members connecting said side reel members at approximately the greatest diameter thereof and adapted to expand the arm of said collapsible reel member upon sliding the collapsible member away from said rigid member and means on said bearing and collapsible member for maintaining same rigid when expanded.

4. An adjustable reel for handling open center coils of wire or like material, comprising an elongated bearing member having grooves on its outer surface, a rigid side reel member secured at one end thereof, a collapsible side reel member having foldable arms and slidably mounted on said bearing member, flexible coil supporting members connecting said side reel members at approximately the greatest diameter thereof and adapted to expand the arms of said collapsible reel member upon sliding the collapsible member away from said rigid member, and means on said collapsible reel member adapted when expanded to engage said grooves on the bearing member.

5. An adjustable reel as described comprising a standard having a base, an upright and a bearing stud, a grooved bearing member journaled on said stud, a rigid side reel member secured at one end of said bearing member, a collapsible side reel member having foldable arms and slidably mounted on said bearing member, flexible coil supporting members connecting said rigid and collapsible reel members at approximately the greatest diameter thereof and adapted to expand the arms of said collapsible reel member upon sliding the collapsible member away from said rigid member, means on said collapsible member adapted to engage the grooves in said bearing member when expanded and means permitting the adjustment of said flexible members.

6. An adjustable reel for handling open center coils of wire or like material comprising an elongated bearing member having a rigid side reel member secured at one end thereof, a side reel member slidably mounted on said bearing member and comprising a hub having arms pivoted thereon, flexible

coil supporting members connecting said rigid side reel member with the outer ends of said pivoted arms of the slidably side reel member whereby movement of said slid-
5 able member away from said rigid member causes said arms to expand.

7. An adjustable reel for handling open center coils of wire or like material comprising an elongated bearing member having secured at one end thereof a rigid side reel member composed of a hub and arms, a side reel member slidably mounted on said bearing member and composed of a hub having pivoted thereon arms of equal number as said rigid reel member, and flexible coil supporting members connecting the outer ends of the corresponding arms of both said reel members, whereby outward movement of the hub of said movable side reel member will cause
20 said pivoted arms to expand.

8. An adjustable reel for handling open center coils of wire or like material comprising an elongated bearing member having secured at one end thereof a rigid side reel member composed of a hub and arms having anchor members at their free ends, a complementary side reel member slidably mounted on said bearing member and composed of a hub having pivoted thereon arms of a number
25 equaling those of the rigid reel member, said arms having a series of openings, the openings of each series having the same radii, anchor members adapted to be secured in said openings, and flexible members fastened at their
30 ends to said anchor members.

In testimony whereof I have hereunto set
my hand this 23d day of October, 1930.

HOWARD E. SHEELEY.
